CORE EXTRACTING DEVICE

Frank Miller, East Orange, N. J., assignor to Ingersoll-Rand Company, Jersey City, N. J., a corporation of New Jersey

Application February 16, 1937, Serial No. 125,995

1 Claim. (Cl. 255—72)

This invention relates to extracting devices, and more particularly to an extracting device for removing the core from a drill hole.

One object of the invention is to enable the core to be expeditiously and securely fastened to the extracting device.

Another object is to enable the gripping element of the extracting device to readily adjust itself with respect to the surfaces against which it seats.

Other objects will be in part obvious and in part pointed out hereinafter.

In the drawing accompanying this specification and in which similar reference numerals refer to similar parts,

Figure 1 is an elevation, partly in section, of a core extracting device constructed in accordance with the practice of the invention and showing a practical application thereof, and

Figures 2 and 3 are transverse views taken through Figure 1 on the lines 2—2 and 3—3, respectively, looking in the direction indicated by the arrows.

Referring more particularly to the drawing, the extracting device, designated in general by 20, comprises a frame or casing 21 adapted to be inserted in a kerf 22, formed by a core drilling tool, and to encircle a core 23 defined by the kerf.

Within the lower end of the casing 21 is a sleeve 24 of which the lower portion 25 of the inner surface is of cylindrical shape and of slightly small diameter than the core 23, and extending from the surface 25 to the upper end of the sleeve 24 is a coniform surface 26 to serve as a seat for a gripping device 27 adapted to engage the periphery of the core 23.

The gripping device 27, in the form illustrated, consists of a plurality of cylindrical members 28 of which the outer surfaces are roughened, as by knurling, to assure firm frictional engagement between the members 28 and the surfaces of the sleeve 24 and the core 23. Each gripping device is provided with a longitudinal bore 29 to receive a flexible, preferably endless, member 30 upon which the gripping devices are arranged. The gripping devices may be freely slidable on the cable 30 or affixed thereto in suitably spaced relation with respect to each other.

In the upper end of the casing 21 is arranged means to reinforce that portion and prevent its distortion or collapse upon the application of power for severing the core from the mass and for lifting the core from the drill hole. The means provided, for illustrative purposes, comprises a cruciform member, designated in its entirety by 31, and comprising a tube 32 of which the ends extend into apertures 33 in diametrically op-

posite sides of the casing near the upper end thereof.

At right angles to the apertures containing the ends of the tube 32 are similar apertures 33 to receive the outer ends of short tube sections 34. 5 The tubes 34 are detachably connected with the intermediate portion of the tube 32 as by affixing plugs 35 in the inner ends of the tube sections 34 and extending reduced stems 36 of the plugs into apertures 37 in the tube 32.

Disposed on the tubes 32 and 34 near their outer ends, as at points adjacent the inner surface of the casing 21, are lifting brackets 38 to which are attached slings 39 which may be connected to a hook 40 carried by a lifting cable 41. 15 The brackets 38 are held against the surface of the casing 21 by collars 42 which, like the brackets, may be loosely slidable on the tubes, and stop members are provided for the collars 42 in the form of pins 43 extending transversely through 20 the tubes 32 and 34.

In the lower portion of the casing and sleeve are registering apertures 44 to accommodate bars or hooks for inverting the casing 21 and effect the ready removal of the core from the casing.

In practice, after the kerf 22 has been advanced 25 a sufficient distance to form a core 23 the drilling tool is removed from the hole and the casing 21 is then lowered to the bottom of the kerf or to a position in which the upper portion of the sleeve 30 lies below the upper end of the core 23, depending upon the length of the core. The gripping members are then inserted between the core and the coniform surface 26 and power may then be applied to the slings 39 for breaking the core 35 from the rock bed and for lifting the core from the drill hole.

After the core and the casing have been placed upon the surface of the ground the pins 43 in the tube sections 34 are removed. The tube sections may then be removed through the apertures in the casing. Thereafter the pins 43 and collars 42 on the tube 32 are removed to permit removal of the latter member from the casing. The upper end of the lifting device is then unobstructed and if then the device 20 is inverted the core 23 will fall through the casing by gravity and thus release the gripping members from the coniform surface 26.

I claim:

A core extracting device, comprising means having an internal inclined surface, an endless flexible member disunited from the said means, and a plurality of gripping members on the flexible member to seat slidably on the inclined surface for gripping a core.
